UNITED STATES PATENT OFFICE

JOHN WILSON BROWN, JR., OF PHILADELPHIA, PENNSYLVANIA

MULTIPLE-DRILLING SPINDLE MACHINE

Application filed March 14, 1930. Serial No. 435,893.

This invention relates to drilling machines, and more particularly to that type of drilling machine wherein a plurality of relatively independent tool units are adapted for synchronous and continuous bodily movement about an axis common to all of the units, each unit embodying a rotatable operating spindle and an opposed work table operating in conjunction therewith.

An important object of the present invention is to provide in a construction of this character an arrangement such that the operating speed of each spindle and the extent of movement of the work table may be regulated to suit the needs of the particular operation to be performed and may be adjusted to vary from the operation of the remaining spindles of the machine.

A further and more specific object of the invention is to provide in a construction of this character an arrangement such that adjustment of the individual spindles may be very readily effected and the extent and timing of movements of the work table may be very closely regulated.

A still further object of the invention is the production of an apparatus of this character which may be very readily and cheaply manufactured, which will be durable and efficient in service and a general improvement in the art.

A further object of the invention is to provide in a construction of this character an arrangement such that regulation of speed of individual spindles may be very conveniently and rapidly accomplished.

These and other objects I attain by the construction shown in the accompanying drawings wherein, for the purpose of illustration, I have shown a preferred embodiment of my invention and wherein:

Fig. 1 is a vertical sectional view through a drilling machine constructed in accordance with my invention;

Fig. 2 is a transverse sectional view through the driving mechanism of the machine;

Fig. 3 is a side elevation of the lower portion of the machine with the guard removed;

Fig. 4 is a view partially in plan and partially in section of the machine;

Fig. 5 is a side elevation of the spindle mounting and the drive mechanism;

Fig. 6 is a detail sectional view through the frame support; and

Fig. 7 is a detail sectional view through the joint of the coolant delivering conduit.

Referring now more particularly to the drawings, the numeral 10 designates a supporting standard about which is rotatably mounted in surrounding relation thereto a carrier 11 which engages the standard through suitable bearings 12 and 13. The upper end of standard 10 rotatably supports a shaft 14 which may be driven from any suitable source and which, through suitable intermediaries 15 and 16, drives shafts 17 and 18. Shaft 18 is equipped with a pinion 19 meshing with a gear 20 mounted upon the upper end of the carrier. At its upper end the carrier rotatably supports a gear 21 which is arranged in surrounding relation to the carrier and which provides a vertically elongated face. This gear at its upper end has secured thereto a bevel gear 22 meshing with a pinion 23 carried by shaft 17.

The carrier immediately below the gear 21 is formed with a plurality of vertically directed slideways 24 in which are mounted for vertical sliding movement, but held against rotation, slides 25. Each slide 25 has rotatably directed therethrough a vertically-extending spindle 26 the upper end of which has rotatably mounted thereon a gear unit comprising gears 27 and 28, of which gear 27 meshes with gear 21. The

upper end of the slide is formed with a flange 29 mounting stud "G" having a compound gear unit including gears 30 and 31, of which the gear 30 meshes with gear 28 of the spindle shaft 26. Gear 31 meshes with a gear 32 secured to the spindle shaft. The gear units are preferably constructed with jaw clutch elements so that they may be readily interchanged to provide the variation of the transmitted speed finally derived at the spindle.

The lower end of each slide 25 is likewise flanged as indicated at 33 and has rotatably directed therethrough a shaft 34 which has a collar 35 abutting the under surface of the flange 33 and which has threaded engagement in the slide guide as at 36. The upper end of shaft 34 is rotatably directed through flange 29 and suitably held against downward movement with relation to such flange as indicated at 37. The lock nut 38 abutting the slide guide serves to secure the slide guide after adjustments have been effected. Through rotation of shaft 34, an end of which is adapted for reception of a wrench, the vertical position of the slide 25 may be regulated, this adjustment being rendered possible by the deep face of gear 21.

Mounted in flange 33 and extending through an opening formed in the overhanging portion of the carrier 11 is a tubular casing 39, the upper end of which has the bore thereof slightly restricted as indicated at 40. Slidable in the bore is the enlarged lower end of the outer section 41 of an extensible plunger, a spring 42 surrounding the plunger between the shoulder provided by the reduction of the bore 40 and the shoulder produced by the enlargement of such outer section so that the plunger is continually urged downwardly. The upper end of the plunger, which is slidable in the restricted portion 40 of the bore, has a head or cap 42-a engaging the upper end of the casing 39 to limit downward movement of the plunger.

The inner section of the plunger is in the form of a sleeve 43 having a shaft 44 rotatably directed therethrough and held against longitudinal movement with relation thereto by means of collars 45, the lowermost collar co-acting with a shoulder formed upon the exterior of the sleeve to maintain the inner section of the plunger against longitudinal movement with relation to a frame 46. The upper end of the shaft is threaded through the cap 42-a and by rotating the shaft which is adapted for the reception of a wrench 47 the effective length of the plunger and, accordingly, the lowermost position of the frame 46 with respect to the spindle shaft 26 may be readily determined.

Frame 46 may move upwardly against the action of spring 42 and is adapted for the support of guards and work guiding devices

as illustrated in my prior patents. Frame 46 may be additionally guided by means of studs 48 carried by the slide 25 and more particularly by flange 33 thereof. Slide guide 24 supports, through vertically-extending conduits 49, an annular coolant trough 50 supplied through pipe 51. The lower ends of conduits 49 telescopically receive, through packed joints 52, the upper ends of coolant tubes 53, the lower ends of which discharge at openings 54 provided for the passage of the spindle shafts or drills, reamers or the like carried thereby.

The lower end of the rotatable carrier embodies an outwardly-extending portion 80 affording beneath each spindle a vertically-directed guide 55 receiving a slide 56, the upper end of which forms a work support 57. The lower end of each slide 56 has a roller 58 co-acting with a cam 59 carried by an associated shaft 60 which is radial to the axis of the carrier and has at its inner end a worm gear 61. The carrier within the enlargement supports vertically-extending worm shafts 62 disposed between each pair of the shafts 60 and each having the worm thereof engaged with the worm gears 61 of the associated shafts. Each worm shaft 62 has at its upper end a pinion 63 meshing with a gear 64 secured to the standard 10 and surrounding same. Cams 59 alternately raise and lower slides 56 to provide space for the insertion of work and to bring the work into engagement with the drill, reamer or the like carried by the associated spindle 26.

It will be obvious that as the carrier and gear 21 are rotated the spindles and their associated work supports will be carried about the axis of the carrier and the spindles will be driven through gear 21 at a rate determined by the gear train comprising gears 27, 28, 30, 31 and 32; simultaneously, the work carriers are raised and lowered to bring the work into engagement with the tools. By adjusting slides 25 the extent of engagement may be very closely determined and this may be further effected by alteration or replacement of cams 59. The position of the work holding frames 46 and the extent of their cooperation with the work holders 57 may be likewise determined by adjustment of the length of the adjustable plunger. In operation, the speed of rotation of the carrier is, of course, relatively low with respect to the speed of rotation of the wide-faced gear. The cams are rotated at such speed that the desired manipulation of the work carriers is effected. With a cam of the type appearing in dotted lines in Fig. 3, rotation of the cam would be co-ordinated with rotation of the carrier.

Since the construction employed is obviously capable of a considerable range of change and modification without in any

manner departing from the spirit of my invention, I do not wish to be understood as limiting myself thereto except as hereinafter claimed.

5 I claim:

1. In a multiple-spindle drill, a rotatable carrier, vertically adjustable spindles mounted in the carrier, a work supporting table associated with each spindle and 10 aligned therewith and carried by said carrier, and means operated by rotation of the carrier for reciprocating the work tables in the general direction of the axis of the carrier including a gear stationary with relation to the carrier, shafts rotating with the carrier and each having a gear meshing with the stationary gear and a cam for each work table, said cams being driven by said shafts.
2. In a multiple-spindle drill, a carrier 20 adapted to rotate about an axis, a co-axial drive gear, a plurality of slides mounted on the carrier, spindles independently adjustable in the slides, gearing connecting each spindle and the first-named gear, means for 25 differentially rotating the carrier and gear, a frame associated with each spindle and carried thereby and means for independently adjusting the frames, yieldable to permit shifting of the frame in the direction of the 30 axis of the spindle, a work table associated with each spindle, means for relatively moving the spindles and work tables to bring work carried by the table into engagement with tools carried by the spindle, said frame 35 engaging work carried by the table of the associated spindle prior to engagement of the tool therewith.
